HIGH-TEMPERATURE TURBOMACHINE

Walter Traupel, Winterthur, Switzerland, assignor to Sulzer Frères, Société Anonyme, Winterthur, Switzerland

Application March 16, 1945, Serial No. 583,163
In Switzerland July 5, 1944

1 Claim. (Cl. 253—69)

1

This invention relates to turbo-machines and in particular to such machines operated by a high temperature working medium and constructed to include at least one stationary interstage division wall supported in the machine by guide blades. The invention consists in that the wall is divided into at least four sectors.

The invention stems from the discovery that in the guide blades which carry the division walls considerably higher peak stresses arise when the walls are divided, according to common practice, into two half discs only, than when they are divided into at least four sectors. The explanation of this unexpected phenomenon is to be sought in the fact that, when the walls are divided into two halves, the centre of the pressure loading on each half disc is so unfavourably placed with regard to the guide blades that, on account of the resulting undulating distortion of the half walls, some of the blades are loaded in a direction contrary to the loading of the others. As a result of the differently directed bending stresses which thus present themselves in the individual blades, maximum stresses arising in particular blades may take on inadmissibly high values.

The disadvantage described is at once eliminated if, as proposed in the invention, the division wall is divided up into at least four sectors. The distribution of the bending stress over the guide blades carrying the single sectors then becomes so nearly uniform that each of the blades is subjected to stressing of approximately the same force and always in the same direction. Abnormally high loading of single blades is thus prevented.

It is expedient for the sectors of the division wall to be so designed that the edges in contact with each other are capable of mutual displacement. Such edges may, for instance, engage with each other by means of tongues and grooves. The guide blades may be connected to the sectors of the division wall either by riveting or by welding.

One embodiment of the invention is illustrated in simplified form in the drawings, in which:

Fig. 1 is a longitudinal section through the complete turbo-machine;

Fig. 2 is a cross-section on the line II—II of Fig. 1;

Fig. 3 is a cross-section on the line III—III of Fig. 2;

Fig. 4 is a perspective of a group of guide blades with attached division wall sector and intermediate piece;

2

Fig. 5 is a perspective of one of the wall sectors; and

Fig. 6 is a perspective of one of the intermediate pieces.

Referring now to Figs. 1 and 2, the casing of the turbo-machine consists of two parts 1 and 2 which are held together with the aid of the flanges 3 and 4. The working medium flows to the casing through the pipe 5 and is led off again through the pipe 6. At the two ends of the machine the lower part 1 of the casing carries the bearings 7 and 8, in which the rotor 9 lies. The shaft 6' and the discs 7', 8' and 9' of the rotor are made in one piece by forging and subsequent machining. To the discs 7', 8' and 9' are attached the rotor blading sets 10, 11 and 12.

Between the sets of rotor blades are the guide blade sets 13 and 14, which carry the division walls 15 and 16 respectively. Each wall is divided into six U-shaped sectors 25, as illustrated particularly in Figs. 2, 4 and 5. Each of the six sectors 25 making up the division wall 15, for example, is held by seven of the guide blades 13. Each guide blade carries at its inner end a rivet 19 by means of which the attached sector of the division wall, in the form of a hollow body, is connected to it.

The radial edges 17 of these sectors, which are in contact with each other, are so formed that they are capable of mutual displacement. As shown in Figs. 3, 4 and 5, the tongues 18 are insertable in the spaces 30 and bridge the spaces of the adjacent sectors 25. As shown in Fig. 2, the several wall sectors 25 are substantially identical, but assembly is facilitated if the intermediate pieces 20 are constructed so that one sector carries two tongues 18, one sector, none, and all the rest of the sectors, one. In this way a gas-tight seal is provided in which the edge of the one sector can be displaced relatively to the edge of the other sector, for instance when the wall is bent or expands from heating.

When the division walls are manufactured the guide blades are first attached by riveting to the U-shaped body of the wall sectors. Next the body of the sector is partly closed by an intermediate piece 20 which is attached by the rivets 21. Part of the intermediate piece 20, which projects beyond the edge 17 of the sector, then forms the tongue 18. The feet 28 of the blades are inserted in grooves of the casing 29 and held by the caulking rings 22, 23. The inner peripheral surfaces of the intermediate pieces 20 have V-shaped grooves 31 cut therein which form a

sort of labyrinth packing for the space between the rotor and the intermediate pieces.

Instead of riveting the blades to the division wall sectors, these might also be welded to the sectors. In principle turbines or pumps or compressors may be manufactured as proposed in the invention. The invention offers special advantages in machines for hot working medium in which the division walls are particularly heavily stressed.

I claim:

In turbo-machines for operating at high temperatures, the improvement which comprises a housing, several rows of guide blades fixed at their exterior peripheries to the housing, a rotor comprising at least two discs with a row of blades on each such disc arranged downstream from a row of said guide blades, a space between each pair of adjacent discs inward of a row of guide blades, an annular division wall in each such space out of contact with the rotor and attached at its outer periphery solely to the guide blades, said

division wall comprising at least four sectors, and intermediate members connected to each such sector with means thereon forming interconnecting slip joints between the adjacent sectors.
